Gifford & Scull

UNITED STATES PATENT OFFICE

ALAN L. BECKET, OF EAST ORANGE, NEW JERSEY

ATTACHMENT PLUG

Application filed January 27, 1928. Serial No. 249,810.

This invention relates to an attachment plug in which the necessity of holding the electric wire to the terminals by means of screws may be dispensed with entirely, or, 5 when the screws or other means are used for attaching the wires to the terminals, the strain on the same is relieved because the wire is clamped by means of elements of the plug so that pull on the cord will not be transmitted to the connectors. At the same 10 time the danger of short circuit between the wires is materially lessened because insulation material is interposed between the ends of the respective wires where they are attached to the metal terminals, and the ends 15 of the wires are farther apart than is usual in devices of this sort. Also, the danger of the wires becoming electrically detached from the terminals is lessened because the 20 wires are retained in a slot between parallel walls that prevent escape of the wire to either side.

The invention will be understood from the description in connection with the accompanying drawings in which Fig. 1 is a perspective view partly broken away of the device with the parts separated, and Fig. 2 is a perspective view of a modified form of one of the details.

30 In the drawings reference character 1 indicates a cap of insulating material that has a cylindrical portion that is screw threaded internally, as indicated at 2, and a rounded or somewhat conically shaped portion that is 35 provided with an opening 3 therethrough.

A plug 4 of insulating material that may be cylindrical in shape is externally threaded as shown at 5, and engages the threads 2 in the cap 1. This plug may be hollow if desired. It is provided with slots or recesses 6 on opposite sides thereof extending axially to accommodate metal terminals 7 that are wide enough to fit the slots closely. Binding screws 8 for holding the bare ends 9 of 45 the wire 10 in place pass through the metal terminals 7 into corresponding screw threaded holes in the plug 4, so that the screws 8 not only keep the wires connected to the terminals 7 but also keep the terminals 7 securely in place. The diameter 50

of the heads of the screws 8 is preferably the same as the width of the slots 6 so that the wires will not move to such positions that the screws would not clamp them in place.

In the modification shown in Fig. 2 the 55 metal terminals 12 corresponding to the terminals 7 are provided with bent-in portions 13 at one end thereof to lie along the lower end of the plug 4. This modification also shows another way by which the wires 60 may be attached to the metal terminals. Each metal terminal may have a tongue 14 struck outwardly therefrom to form a slit into which the end of the bare wire may be slipped and kept in place by friction. Any 65 other convenient means, such as solder, for example, may be used for keeping the ends of the bare wires into electrical contact with the terminals and it is not necessary for the terminals to be screwed in place in the slots 70 or recesses in the plug 4.

In assembling the device the cord 10 is passed through the hole 3 in the cap 1 and the wires 9 separated and the insulation stripped off. The wires can be attached to 75 the metal terminals 7 by means of the screws 8 or in any other convenient manner as the terminals are readily accessible with the plug 4 out of the cap 1. After the wires are attached the cap 1 is screwed on until the 80 surface 15 thereof presses the spread ends of the wires 9 firmly in contact with the bottom of the plug 4, thus relieving any strain on the connection of the wires to the metal terminals 7.

It is obvious that the wire 10 can be pulled with safety for the purpose of withdrawing the metal contact 7 from the sockets into which they have been inserted. The bare 85 ends of the wires 9 are separated considerable distances and have solid insulating material interposed between them. The terminals 7 are securely held in the slots or recesses 6, and the portions thereof to which the wires 9 are connected are entirely covered with the insulating material of the cap 1 so as to protect the same both mechanically and electrically. The device is more 90 convenient to assemble than other devices of this sort and may be made smaller than 100

the present plugs, thereby saving material. In addition, the fiber insulating disc that is common with devices of this sort is eliminated.

I claim:

1. An attachment plug comprising a screw threaded cap and a screw threaded plug, said plug being provided with recesses on the opposite sides thereof and electrical terminals seated therein, said terminals being provided with tongues for engaging electric wires, the ends of said tongues engaging said cap when it is in place.
2. An attachment plug comprising a screw threaded cap and a screw threaded plug interrupted along its outer periphery, electric terminals carried on the sides of said plug at the places where said threads are interrupted, and electric wires clamped to said terminals, said cap pressing against said wires and terminals.

ALAN L. BECKET.
